UNITED STATES PATENT OFFICE

ROBERT I. EUSTIS, OF LOS ANGELES, CALIFORNIA, ASSIGNOR OF ONE-HALF TO MORRIS NELSON, OF LOS ANGELES, CALIFORNIA

DRAWER GUIDE

Application filed June 29, 1927. Serial No. 202,249.

This invention relates to improvements in drawer guides.

An object of the invention is to provide a drawer guide of novel construction which will enable a drawer to be completely withdrawn from within the structure supporting it and which will rigidly support the drawer in its withdrawn position.

Another object of the invention is to provide a drawer guide of novel and simple construction which may be easily, quickly and cheaply manufactured, and which may be easily and quickly applied to a drawer.

A further object of the invention is to provide a drawer guide having the above mentioned characteristics, which occupies a very small amount of space between the sides of the drawer and the sides of the supporting structure.

Another object of the invention is to provide a drawer guide in which there is a stationary member and a slidable member, and which slidable member will have positive engagement with the stationary member, yet by tilting of the same, it may be caused to release its engagement therewith.

With these and many other objects in view which will more readily appear as the nature of the invention is better understood, the same consists in the novel construction, combination, and arrangement of parts, which will hereinafter be more fully described, illustrated, and claimed.

The essential features of the invention involved in the carrying out of the objects indicated are susceptible to modification; but a preferred embodiment of the invention is shown in the accompanying drawings, in which:

Figure 1 is a sectional view taken through a supporting structure having a drawer mounted therein, showing my invention as applied to the structure and to the drawer.

Fig. 2 is a sectional view taken along the line 2—2 of Figure 1, and

Figs. 3 and 4 are respectively, perspective views of the two elements that co-operate to make up my improved drawer guide construction.

In manufacturing the combination device,

while the various elements thereof may be constructed in any suitable manner and of any suitable material, yet it is preferable to form the same from sheet-metal stampings on account of the cheapness, lightness and strength of the latter; but irrespective of these details in manufacturing, the essential features of the invention are always preserved.

In the accompanying drawings like reference characters designate like parts throughout, and the supporting structure may be of any desired form such as in a table, cabinet, cupboard or the like. In the present instance it is illustrated as consisting of a pair of side walls one of which is shown at 10 and which has a vertical member 11 thereon. The drawers are shown at 12 and are adapted to be slidably supported between these strut members. My novel drawer guide consists of a stationary element 13 attachable to the vertical strut 11 and a movable element 13' which is channel-shaped in cross section, and is adapted to engage loosely a bottom edge of the drawer.

The stationary member 13 comprises a flat plate having apertures 14 therethrough for the reception of wood screws or the like, whereby the same may be attached to the vertical strut 11. A laterally extending flange 15 serves as a steadyng member and engages one face of the vertical strut. A supporting flange is designated at 16, which flange is formed by cutting out a portion of the flat plate and striking up the same.

The outer end of the supporting flange 16 has a small upstanding portion 17 which has its upper edge inclined rearwardly and downwardly from the horizontal at an angle of approximately 15°. A narrow thrust flange is designated at 18, which flange is located rearwardly of the supporting flange 16 and spaced upwardly therefrom a convenient distance. This flange 18 is provided from a cut-out portion 19 in the plate, and at its outer edge is provided with a downwardly extending flange 20 similar to the flange 17. This flange 20 has its edge extending rearwardly and downwardly that is parallel to the edge of the flange 17.

100

The movable member 13' is adapted to be supported upon the supporting flange 16 and between this flange and the flange 18. This movable member comprises a strip of sheet metal, channel-shaped in cross section, having a horizontal flange 25 and a vertical flange 26. A pair of upstruck lugs 37 and 38 are provided on the flange 25, and a similar lug 38' is provided on the vertical flange 26 for purposes to be described later. The transverse width of the flange 26 is exactly equal to the vertical distance between the flanges 16 and 18, and the transverse width of the flange 25 is approximately equal to the lateral distance between the flange 17 and the flat face of the member 13. A supporting block 41 fastened to the structure 11 is disposed immediately below the supporting flange 16 and gives additional support to said flange as well as the slidable member 13' and the drawer 12.

The foregoing description definitely sets forth the structure of my improved drawer guide, and I will now proceed with a description of the operation of the drawer guide and its application to a drawer structure.

In installing the device the drawer guide is disposed between the drawer and the structure supporting the same, and in a similar manner, another drawer guide which is a counterpart of the first mentioned guide, is disposed between the other side of the drawer and the structure. The second drawer guide does not appear in the drawings, but is constructed as a counterpart. When the member 13 has been attached to the strut, the member 13' is inclined rearwardly and inserted between the flange 16 and the flange 18 so that the flange 20 overlies the vertical portion of the member 13', and the flange 17 engages the edge of the horizontal portion. The member 13 is then slidably locked to the member 13' and can be removed, therefrom only by tilting the same rearwardly to clear the flanges 17 and 20. The drawer structure is loosely disposed with a lower edge in the angle of the member 13'. A strip 29 is attached to the under side of the drawer and acts as a stop to prevent the drawer from being entirely withdrawn from the supporting structure. This strip 29 is adapted to bear with its forward end 35 against the upstruck lug 37 before referred to. The lug 38' similarly prevents bodily removal of the movable element 13' since the same is adapted to abut against the flange 20 when the movable member is extended. A groove 36 is cut in the side of the drawer to accommodate the flange 20 and to prevent friction between the same and the side of the drawer. The upstanding lug 38 acts as a guide and engages one edge 40 of the drawer structure and holds the same firmly against the side 26 of the piece 13'.

In actual operation when installed, the

drawer will slide upon the movable member 13' before the movable member slides within the stationary member 13. When the strip 29 engages the lug 37, the slidable member 13' will slide within the stationary member 13 until such a time as the lug 38' engages the flange 20. In closing the drawer, the drawer will first slide upon the slidable member 13' until the front wall of the drawer engages the front end of the slidable member 13', and forces the latter rearwardly within the stationary member 13. When the drawer is removed, the slidable member 13' may easily be removed from the stationary member 13 by inclining the former rearwardly and moving the same laterally between the flange 20 and the flange 17.

From the foregoing, it is thought that the construction, use and many advantages of the herein-described drawer guide will be readily apparent without further description, and it will also be understood that changes in the form, proportion, and minor details of construction may be resorted to without departing from the spirit of the invention or sacrificing any of the advantages thereof.

What I desire to claim by this invention and secure by Letters Patent is:

1. A drawer guide comprising in combination a plate having a supporting flange thereon, a thrust flange on said plate above said supporting flange, a downwardly extending flange on said thrust flange, an upwardly extending flange on said supporting flange, a slidable member angular in cross section supported between said supporting flange and said thrust flange, a stop on said slidable member adapted to engage a drawer, a second stop on said slidable member adapted to engage said downwardly extending flange as and for the purpose specified. 95

2. The combination with a drawer having a strip attached to the under side of the same, and a supporting structure for the drawer, of a plate attachable to said supporting structure, a comparatively wide supporting flange on said plate, a narrow thrust flange on said plate, a downwardly extending wedge-shaped flange on said thrust flange, and an upwardly extending wedge-shaped flange on said supporting flange, a slidable member angular in cross section having a vertical and horizontal flange receivable between said supporting flange and said thrust flange, said vertical flange lying against said plate beneath said thrust flange, said horizontal flange lying against said supporting flange, said wedge-shaped flanges serving to retain said slidable member in position, a lug on said horizontal flange adapted to engage said strip on said drawer to limit the movement of the drawer, a lug on said vertical flange adapted to engage said downwardly extending wedge-shaped flange, as and for the purpose specified. 100 110 115 120 125 130

3. The combination of a drawer provided with a side edge extending below the bottom of the drawer, a supporting structure for the drawer, a plate fast to the supporting structure, a supporting flange on said plate with a vertical flange in the shape of a wedge with its apex to the rear, a narrow thrust flange on said plate, said thrust flange being above and in the rear of said supporting flange and provided with a downwardly extending vertical flange in the shape of a wedge with its apex in front, the side of the drawer having a groove for the reception of said thrust flange in sliding engagement therewith, a channel shaped member slidable in said supporting flange and said thrust flange, a stop flange mounted in the rear of said slidable member to engage the thrust flange and to limit the forward movement of the slid-
 5 able member, a stop flange extending from the front of said slidable member, a stop on the under side of the drawer to engage said last named flange to limit the forward movement of the drawer, and a guide flange on the slid-
 10 able member for engaging the side edge of the drawer.
4. The combination of a drawer, a supporting structure for the drawer, a supporting flange secured to and extending horizontally from said supporting structure and provided with a vertical flange, a narrow thrust flange secured to said supporting structure, said thrust flange being above and in the rear of said supporting flange and provided with a downwardly extending vertical flange, the side of the drawer having a groove for the reception of said thrust flange in sliding engagement therewith, a member slidable in said supporting flange and said thrust flange, means on said slidable member to engage the thrust flange to limit the forward movement of the slidable member, and means extending from the front of said slidable members to engage and limit the forward movement of the drawer.
5. The combination of a drawer, a supporting structure therefor, a horizontal supporting flange secured to said supporting structure and provided with a vertical flange, a narrow thrust flange secured to said supporting structure and disposed above and in the rear of said supporting flange and provided with a downwardly extending vertical flange, a channel shaped member slidable in said supporting flange and said thrust flange, a stop mounted in the rear of said slidable member to engage the thrust flange and to limit the forward movement of the slid-
 15 able member, and a stop extending from the front of said slidable member to limit the forward movement of the drawer.
6. The combination of a drawer provided with a side edge extending below the bottom of the drawer, a supporting structure for the drawer, a horizontal supporting flange secured to said supporting structure and provided with an upwardly extending vertical flange, a horizontal thrust flange secured to said supporting structure and disposed above and in the rear of said supporting flange and provided with a downwardly extending vertical flange, the side of the drawer having a groove for the reception of said thrust flange in sliding engagement therewith, a member slidable in said supporting flange and said thrust flange, means on said slidable member to limit the forward movement of the slid-
 20 able member, means extending from the front of said slidable member to limit the forward movement of the drawer, and a guide flange on the slidable member for engaging the side edge of the drawer.
7. The combination of a drawer, a supporting structure therefor, a horizontal supporting flange secured to said supporting structure and provided with an upwardly extending vertical flange, a horizontal thrust flange on said supporting structure disposed above said supporting flange and provided with a downwardly extending vertical flange, the side of the drawer having a groove for the reception of said thrust flange in sliding engagement therewith, a member slidable in said supporting flange and said thrust flange, means on said slidable member to engage the thrust flange to limit the forward movement of the slidable member, and means extending from the front of said slidable members to engage and limit the forward movement of the drawer.
8. A drawer structure comprising means providing a drawer receiving compartment having supports at its sides, members each providing a bottom and a side movable upon the supports, means limiting the forward movements of said members, a drawer movable over the bottoms of said members, and means disposed between the bottom of the drawer and the bottoms of said members adapted to engage, for limiting the forward movement of the drawer relatively to said members.
9. A drawer structure comprising means providing a drawer receiving compartment having supports at its sides, members each providing a bottom and a side slidable upon said supports, means extending laterally from the side of each member adapted to engage a stop on the compartment to limit the forward movements of said members, a drawer movable upon the bottoms of said members, and means on the bottom surface of the drawer arranged remotely from its rear end and the bottoms of said members adapted to engage, to limit the forward movement of the drawer relatively to said members.
10. A drawer structure comprising means providing a drawer receiving compartment

- having supports at its sides, members each providing a bottom and a side slidable upon said supports, means extending laterally from the side of each member adapted to engage a stop on the compartment to limit the forward movements of said members, and a drawer movable upon the bottoms of said members, there being means forming a stop extending vertically with respect to the bottoms of said members adapted to be engaged by a complementary stop on the bottom of the drawer located a material distance forwardly of its rear end to limit the forward movement of the drawer relatively to said members. 15 70 75
11. A drawer structure comprising means providing a drawer receiving compartment having supports at its sides, members each providing a side and a bottom slidable upon said supports, a portion of the side of each member being bent laterally forming a stop above the bottom and adjacent the rear engageable with the stop on the compartment to limit the forward movements of said members, a drawer slidable upon the bottoms of the members, and a portion of the bottom of each member being bent upwardly to form a stop adapted to engage a stop on the drawer. 20 80 85 90 95
12. A drawer structure comprising means providing a drawer receiving compartment having supports at its sides, members each providing a side and a bottom slidable upon said supports, a portion of the side of each member above its bottom being bent laterally forming a stop engageable with the stop on the compartment to limit the forward movements of said members, a drawer slid- 35 able upon the bottoms of the members, and a portion of the bottom of each member being 40 bent upwardly to form a stop adapted to engage a stop on the bottom of the drawer. 100 105 110
13. A drawer structure comprising means providing a supporting structure having sides and supports adjacent its sides, members slidable upon the supports having sides and bottoms, the sides of said members being positioned adjacent to and being engageable with the sides of the supporting structure, a drawer presenting flat sides from 45 which no protuberances extend slidable on said members and having its sides positioned adjacent the sides of said members and engageable therewith, means extending laterally from the sides of said members above 50 the bottoms thereof forming stops engageable with stops on the supporting structure to limit the forward movements of said members, and means extending upwardly from the bottoms of said members forming stops engage- 55 able with stops on the under surface of the drawer to limit the forward movement of the drawer relatively to said members. 60 120 125
14. A drawer construction comprising means providing a drawer receiving chamber, supports at the sides of the chamber, 65 members slidable upon the supports, a drawer having sides and a bottom, the sides extending downwardly below the bottom and slidably resting upon the members, means limiting the forward movements of said members relatively to the supports, and means extending upwardly from said members and arranged between the sides of the drawer adapted to be engaged by a part on the drawer to limit the forward movement of the drawer relatively to said members. 70 75 80 85 90 95 100 105 110 115 120 125 130

In testimony whereof I have signed my name to this specification.

ROBERT I. EUSTIS.
